Primary Examiner — Elizabeth J Oswecki*Assistant Examiner* — Lacey Chey Bowman(57) **CLAIM**

The ornamental design for a dash cam, as shown and described.

DESCRIPTION

FIG. 1 is a top perspective view of a dash cam showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets(56)
